UNITED STATES PATENT OFFICE.

CHARLES C. BLAKE, OF BROOKLINE, MASSACHUSETTS.

WELTING.

1,408,797.

Specification of Letters Patent.

Patented Mar. 7, 1922.

Application filed March 29, 1918. Serial No. 225,572.

To all whom it may concern:

Be it known that I, CHARLES C. BLAKE, a citizen of the United States, residing at Brookline, in the county of Norfolk and State of Massachusetts, have invented certain Improvements in Welting, of which the following description, in connection with the accompanying drawings, is a specification, like reference characters on the drawings 10 indicating like parts in the several figures.

The present invention relates to welting which is used in the manufacture of welt shoes, and more particularly to welting used in the manufacture of Blake welt shoes.

15 In making a Blake welt shoe there are two operations which particularly distinguish from the manufacture of Goodyear welt shoes. These operations are lasting and inseam sewing. In the lasting operation the upper is updrawn to stretch the upper to the wood of the last and then the stretched upper is secured to the edge face of an insole on the bottom of the last. In the inseam sewing operation a welt is secured to the lasted shoe 25 so that the flesh faces of the welt and insole are in the same plane.

The object of the present invention is to produce a welt for a welt shoe by means of which a better joint can be made between 30 the upper of the lasted shoe and the edge face of the welt engaged thereby.

To the accomplishment of this object, and such others as may hereinafter appear, the features of the invention relate to certain 35 constructions, arrangements and methods of manufacture hereinafter described and then set forth broadly and in detail in the appended claims which possess advantages readily apparent to those skilled in the art.

40 The various features of the present invention will be readily understood from an inspection of the accompanying drawings, in which,

Figure 1 is a perspective of a strip of welting embodying the features of the present invention, and

Fig. 2 is a sectional elevation illustrating the operation of attaching the welt shown in Fig. 1 to a Blake lasted welt shoe.

50 In the manufacture of a Blake welt shoe an insole 1 is secured to the bottom 2 of a last 3 and an upper 4 is stretched on the top of the last and then secured in its stretched condition to the edge face 5 of the insole.

The next operation is the inseam sewing 55 operation wherein a welt 6 is secured to the lasted shoe. To this end the welt 6 is provided with a longitudinal slit 7 formed along the edge face 8 which is exposed in the finished shoe. The welt is secured to the lasted 60 shoe by a single thread 9 passing through the welt, upper and insole and anchored in the base of the slit 7 of the welt and on tongues 10 formed in the flesh face of the insole.

Heretofore the edge face of the welt which 65 engaged the upper 3 of the lasted welt shoe was normal to the top and bottom faces of the welt. With this construction it was discovered that after the welt was secured to the lasted shoe the edge face of the welt had become 70 convex owing to the bulging of the leather caused by the introduction of the stitches. This convex edge face of the welt allowed the welt to rock on the upper and somewhat affected the appearance of the 75 joint between the welt and the upper.

To avoid this difficulty I propose to concave the edge face 11 of the welt engaged by the upper as shown at 12, Fig. 1. With this construction when the welt is drawn up tight 80 against the lasted welt shoe the edge face 11 becomes normal to the top and bottom faces of the welt thus making a good joint with the upper.

I propose to provide the welt 6 with the 85 slit 7 and concave 12 simultaneously as in that way the tendency of the slitting and concaving tools to distort the welt may be counteracted.

While it is preferred to employ the specific 90 construction, arrangement and method of manufacture shown and described, it will be understood that this specific construction, arrangement and method of manufacture is not essential nor is the conjoint use of all the 95 features of the invention essential except so far as specified in the appended claims and it may be varied or modified without departing from the broader features of the invention.

100 What is claimed as new, is:

1. A welt for a welt shoe provided with a concaved edge face, the top and bottom edges of said concaved edge face lying in the same vertical plane parallel to the other edge face 105 of the welt.

2. A welt for a welt shoe provided with a concaved edge face, the top and bottom

edges of said concaved edge face lying in the same vertical plane parallel to the other edge face of the welt, said concaved edge face being opposite the edge face of the welt which is exposed in the finished shoe.

3. A welt for a welt shoe provided with a longitudinal slit along the edge face which is exposed in the finished shoe and having

that edge face which is opposite the slit edge face concaved.

10

4. A welt for a welt shoe having plain top and bottom faces and edge faces slit and concaved longitudinally, respectively.

In testimony whereof I have signed my name to this specification.

CHARLES C. BLAKE.
